RELEASE DEVICE FOR WRINGERS

Walter L. Kauffman, III, Erie, Pa., assignor to
Lovel Manufacturing Company, Erie, Pa., a
corporation of Pennsylvania

Application March 17, 1937, Serial No. 131,333

14 Claims. (Cl. 68—263)

Power wringers are commonly provided with safety release mechanisms by which the pressure on the rolls may be instantly released. Many of these devices effect a release by releasing the top bar from the frame, and the release mechanisms in such structures ordinarily involve latching devices which may be released to permit the separation of the top bar and with such a separation a release of pressure on the rolls. Such a device is shown in my former application No. 670,461 dated May 11, 1933, on which patent issued July 27, 1937, No. 2,087,977, and in some respects the present invention is an improvement over the structure of that application. In that application the release latching mechanism would not automatically permit the escapement of the engagement parts so that the resetting could automatically be accomplished without manipulation of the engaging portions of the latching structure. With the present invention, while the release may be perfectly effected, the resetting of the parts after release is accomplished without any manipulation of the latches through an escapement relation of these parts. Features and details of the invention will appear from the specification and claims.

A preferred embodiment of the invention is illustrated in the accompanying drawings as follows:

30 Fig. 1 shows a front elevation, part being broken away to better show construction.

Fig. 2 an enlarged section on the line 2—2 in Fig. 1.

Fig. 3 an enlarged view of the latching end of the top showing the latching mechanism in set position.

Fig. 4 an enlarged view of the end of the top showing the latch mechanism released, and the parts being in the position formed prior to resetting.

Fig. 5 shows a similar view with the parts in an intermediate position during the resetting operation.

The wringer has a frame consisting of a base 1, 45 and side stiles 2 and 3. A lower roll 4 and an upper roll 5 are provided, the lower roll having a shaft 6 journaled in bearings 7, the bearings 7 being arranged in the side stiles. The upper roll 5 has a shaft 8 which operates in bearings 9 slid- 50 ingly mounted in the side stiles. A spring 10 rests on the upper bearings and exerts pressure from the top bar 11 through an adjusting screw 12, the screw operating through a nut 13 in the top bar.

55 A resetting device is arranged for resetting the

pressure on the top bar. This comprises a toggle lever, the actuating lever 14 of which is provided at 15 on the top bar. A link 16 is pivotally connected by screw 18 with the side stile 3 and with the lever 15 by screw 17. The lever 15 is channel form and closes over the side stile, and the link 16 is also of channel form, the sides being connected by plate 19. It can be readily seen that as the lever mechanism is open the end of the top bar is free to rise from the stile, but as the levers are swung to their set position as shown in Fig. 1, the top bar is drawn into pressure position, the leverage increasing as the pressure on the spring increases.

A release mechanism is provided for the opposite end of the top bar. A latch member 20 is provided with a slot 21 which has portions 22 and 23 extending each side of a pivot pin 24 when the latch member is in set position as shown in Figs. 1 and 3. These portions 22 and 23 are preferably inclined with the apex at the set position. The latch member is of channel form having the sides 20a and connecting plate 20b. Hooks 25 are formed on the sides 20a and are adapted to enter notches 26 in the upper inner corners of the stile 2, the hooks engaging the shoulders formed by the upper end of the notch, the plates having cut-away portions 30 to clear the portion of the side stile above the notch.

The latch has a trip finger 27 which is adapted to engage the under-side of a cross member 28 forming a portion of the trip member. The trip member retains the latch in set position holding it against the urge for releasing through the pressure of the main spring 10 and the relation of the surfaces of the hooks 25 of the latch with the upper wall of the notch 26. The cross member extends through slots 29 in the top and extends into an operating bar 31 at the front and rear of the wringer and forming the operating bars. A companion cross member 28a extends through slots 29a, and the cross member 28 is secured in the operating member 31. The cross members 28 and 28a have cam surfaces 32 which are adapted to engage the ends of the slots 29 and 29a respectively when either cross member is moved inwardly, and through this engagement to move the trip cross plate 28 endwise sufficiently to release the finger 27 and permit the inner end of the latch to swing upwardly so as to release the hook 25 and consequently the top bar from the side stile. This release of the release end of the top bar as it swings up moves the pivot 15 outwardly endwise so as to bring this pivot beyond the alignment between pivots 17 and 18.

and thus effects the release of the resetting mechanism and this permits the further opening of the top bar to free the wringer rolls from pressure. A spring 33 is secured to the cross plate 28a and yieldingly draws the top member comprising the cross plates 28, 28a and the connecting operating members 31 toward the right or set position. The cross plate 28 has a lip 34 which forms an inclined surface on the upper part of the cross plate 28. A pin 35 extends through an opening 36 in the connecting plate 20b. This pin is provided with a head 37, and a spring 38 is tensioned between the head 37 and the connection plate 20b, thus yieldingly pressing the inner end of the latch downwardly. As soon as the top moves upwardly and the hook has cleared the upper end of the stile the spring 38 presses down the inner end of the latch, and the finger 27 operating on the incline 34 crowds the latch toward the right sufficiently to permit the finger to clear the cross plate 28. The portion of the slot 23 permits the end movement for this clearance. The downward movement of the inner end of the latch is obstructed by stop 39 riveted on the under-side of the cross plate 28. As soon as the inner end of the latch reaches this stop the further pressure of the spring 38 pressing downwardly on the latch effects a movement of the latch toward the left by reason of the inclined or camming surfaces in the portion 22 of the pivot slot.

As the top is reset the bottom of the hook 25 engages the top of the stile. This under-side of the hook has a cam surface 25a which forces the latch toward the left so that the hook may clear the inner face of the stile. The portion 23 of the pivot slot permits this endwise movement. The hook is yieldingly carried into the notch 26 by the pressure of the spring 38 and the camming action of the portion of the slot 23 on the pin 24 thus bringing the parts to the position of engagement shown in Figs. 1 and 3, and as the pressure of the main spring is exerted on the top the pin 24 seeks the upper or apex of the slot retaining the engagement of the hook in the notch and also the position of the finger 27 under the trip plate 28. It will be noted that an inward movement of either operating member 31 forces the endwise release movement of the trip plate 28. If the operating members 31 are hit toward the ends only one of the cammed surfaces 32 may be brought into active operation so as to effect this endwise movement. In any event, the operation of operating bar 31 effects this endwise movement either through an inner movement of one of the other cross plates or by both of them. The endwise yielding of the trip members on trip plate 28 through the incline 34 may permit of the resetting of the finger relatively to the trip plate but in this case the spring 38 would have to be of such stiffness as to overcome the force of the spring 33 resisting the endwise movement of the trip plate 28.

The trip member which responds with an endwise movement when forced inwardly, broadly considered, forms the subject matter of a companion application filed March 17, 1937, Serial No. 131,334.

This application is a part and continuation of application 45,282, filed October 16, 1935.

What I claim as new is:

1. In a wringer, the combination of a frame comprising a rigid top bar; rolls mounted in the frame; pressure means for the rolls exerting pressure from the top bar; means securing the

top bar to and releasing it from the frame at an end of the top bar comprising an unstable latch member latching the end of the top bar to the frame; a mounting connecting the latch to the top bar; a trip member retaining the latch member in set position; a mounting on the top bar for the trip member; and an operating member actuating the trip member, the mountings, latch, and trip members being related to automatically provide for the resetting of the latch member as the top bar is moved to set position. 5

2. In a wringer, the combination of a frame comprising a rigid top bar; rolls mounted in the frame; pressure means for the rolls exerting pressure from the top bar; means securing the top bar to and releasing it from the frame at an end of the top bar comprising an unstable latch member latching the end of the top bar to the frame; a mounting connecting the latch to the top bar; a trip member retaining the latch member in set position; a mounting on the top bar for the trip member; and an operating member actuating the trip member, the mountings automatically providing for relative movements of the members for clearing the engaging portions of the latch and trip member with a resetting movement of the top bar. 15

3. In a wringer, the combination of a frame comprising a rigid top bar; rolls mounted in the frame; pressure means for the rolls exerting pressure from the top bar; means securing the top bar to and releasing it from the frame at an end of the top bar comprising an unstable latch member latching the end of the top bar to the frame; a mounting connecting the latch to the top bar; a trip member retaining the latch member in set position; a mounting on the top bar for the trip member; and an operating member actuating the trip member, the mountings automatically providing relative endwise movements of the members for clearing the engaging portions of the latch and trip member with a resetting movement of the top bar. 30

4. In a wringer, the combination of a frame comprising a rigid top bar; rolls mounted in the frame; pressure means for the rolls exerting pressure from the top bar; means securing the top bar to and releasing it from the frame at an end of the top bar comprising an unstable latch member pivoted between its ends to the top bar, 35 having a short arm sustaining from the pivot the major portion of the pressure at its end of the top bar, and a long arm to which the pressure is communicated; a trip device on the top bar operating on the long arm; and an operating member actuating the trip device, the latch and trip member being related to automatically permit the resetting of the top bar and latch member. 50

5. In a wringer, the combination of a frame comprising a top bar; rolls mounted in the frame; pressure means for the rolls exerting pressure from the top bar; means securing the top bar to and releasing it from the frame at an end of the top bar comprising a latch member pivoted 55 through a slot and pin connection intermediate its ends to the top bar and engaging the stile, said latch having a short arm sustaining from the pivot the major portion of the pressure at its end of the top bar, and a long arm to which pressure is communicated; a trip device operating on the long arm; and an operating bar actuating the trip device, said slot and pin connection permitting endwise movement of the latch for automatically clearing the latch rela- 70 75

tively to the stile and the trip device in resetting the latch as the top bar is moved to position.

6. In a wringer, the combination of a frame comprising a top bar; rolls mounted in the frame; pressure means for the rolls exerting pressure from the top bar; means securing the top bar to and releasing it from the frame at an end of the top bar comprising a latch member pivoted through a slot and pin connection intermediate its ends to the top bar and engaging the stile, said latch having a short arm sustaining from the pivot the major portion of the pressure at its end of the top bar, and a long arm to which pressure is communicated; a trip device operating on the long arm; and an operating bar actuating the trip device, said slot and pin connection providing endwise movement of the latch for automatic clearing of the latch with relation to the stile and the trip device for resetting of the latch as the top bar is moved to position, the slot extending each side of the position of the pin with the latch in set position and permitting endwise movement of the latch in one direction to clear the trip device, and endwise movement in the opposite direction to clear the frame as the top is moved to position.

7. In a wringer, the combination of a frame comprising a top bar; rolls mounted in the frame; pressure means for the rolls exerting the top bar to and releasing it from the frame at an end of the top bar, comprising a latch member pivoted through a slot and pin connection intermediate its ends to the top bar and engaging the stile, said latch having a short arm sustaining from the pivot the major portion of the pressure at its end of the top bar, and a long arm to which pressure is communicated; a trip device operating on the long arm; and an operating bar actuating the trip device, said slot and pin connection permitting endwise movement of the latch for automatic resetting of the latch as the top bar is moved to position, the slot extending each side of the position of the pin with the latch in set position and permitting endwise movement of the latch in one direction to clear the trip device, and endwise movement in the opposite direction to clear the frame as the top is moved to position, the sides of the slot being inclined from each other, the force of the pressure means urging the pin to set position at the apex.

8. In a wringer, the combination of a frame comprising a top bar; rolls mounted in the frame; pressure means for the rolls exerting pressure from the top bar; means securing the top bar to and releasing it from the frame at an end of the top bar comprising a latch member latching the end of the top bar to the frame; a mounting connecting the latch to the top bar; a trip member retaining the latch member in set position; a mounting for the trip member on the top bar; and an operating member providing clearance for the latch in relation to its engagement with the stile and trip device in an engaging movement of said latch endwise of the wringer, the mountings, latch and trip members being related to automatically permit the resetting of the top bar and the latch member.

9. In a wringer, the combination of a frame comprising a top bar; rolls mounted in the frame; pressure means for the rolls exerting pressure from the top bar; means securing the top bar to and releasing it from the frame at an end of the top bar comprising a latch member latch-

ing the end of the top bar to the frame; a mounting connecting the latch to the top bar; a trip member retaining the latch member in set position; a mounting for the trip member; an operating member actuating the trip member, the mountings, latch and trip members being related to automatically provide for the resetting of the top bar and the latch member; and a pressure setting device acting on the top bar at the opposite end of the wringer from the latch with the latch engaged.

10. In a wringer, the combination of a frame, the top bar detachably mounted on the frame; wringer rolls in the frame; mechanism exerting pressure on the rolls from the top bar; means securing the top bar to the frame comprising a pivoted latch in the form of a lever fulcrumed at the pivot, said latch forming the latch connection between the top bar and the frame and imparting top bar pressure to the pivot of the latch and a trip device securing the latched lever in set position and subjected to top bar pressure through leverage of the latch, said securing means having its parts related to automatically assume a locking position as the top bar is placed on the frame.

11. In a wringer, the combination of a frame, the top bar detachably mounted on the frame; wringer rolls in the frame; mechanism exerting pressure on the rolls from the top bar; means securing the top bar to the frame comprising a pivoted latch in the form of a lever fulcrumed at the pivot to said top bar, said latch forming the latch connection between the top bar and the frame and imparting top bar pressure to the pivot of the latch; and a trip device on said top bar securing the latched lever in set position and subjected to top bar pressure on the latch, said latch being movable crosswise of the pivotal axis of said latch to clear the trip device for resetting.

12. In a wringer, the combination of a frame, the top bar detachably mounted on the frame; wringer rolls in the frame; mechanism exerting pressure on the rolls from the top bar; means securing the top bar to the frame comprising a pivoted latch in the form of a lever fulcrumed at the pivot to said top bar, said latch forming the latch connection between the top bar and the frame and imparting top bar pressure to the pivot of the latch; and a trip device on said top bar securing the latched lever in set position and subjected to top bar pressure on the latch, said latch being movable crosswise of the pivotal axis of said latch to clear the trip device for resetting and automatically returning to normal position relatively to the axis for setting the latch.

13. In a wringer, the combination of a frame, the top bar detachably mounted on the frame; wringer rolls in the frame; mechanism exerting pressure on the rolls from the top bar; means securing the top bar to the frame comprising a pivoted latch in the form of a lever fulcrumed at the pivot to said top bar, said latch forming the latch connection between the top bar and the frame and imparting top bar pressure to the pivot of the latch; and a trip device on said top bar securing the latched lever in set position and subjected to top bar pressure on the latch, said latch being movable crosswise of the pivotal axis of said latch to clear the trip device for resetting and automatically returning to normal position relatively to the axis for setting the latch, and automatically returning the latch to set position under pressure.

14. In a wringer, the combination of a frame comprising side stiles; a top bar detachably mounted on the frame; wringer rolls in the frame; mechanism exerting pressure on the rolls from the top bar; a trip device; means securing the top bar to the frame comprising a latch pin secured to the top bar and offset from the inner face of the stile with the top in position on the stile; and a latch having a free end engaged by 10 the trip device, said latch being pivoted on the

pin with an elongated inclined slot permitting endwise movement of the latch, said latch having a catch shoulder having an inclined surface adapted to engage a shoulder on the stile, said latch through the location of the pin, the inclination of the slot and the catch shoulder moving the latch endwise to clear the trip device automatically for re-setting. 5

WALTER L. KAUFFMAN, II. 10
